UNITED STATES PATENT OFFICE.

ELMER L. DENNIS, OF ROCKFORD, ILLINOIS, ASSIGNOR TO ANDREWS WIRE & IRON WORKS, OF ROCKFORD, ILLINOIS, A CORPORATION OF ILLINOIS.

SOAP-TRAY.

1,249,603.

Specification of Letters Patent. Patented Dec. 11, 1917.

Application filed February 10, 1917. Serial No. 147,877.

To all whom it may concern:

Be it known that I, ELMER L. DENNIS, a citizen of the United States, residing at Rockford, in the county of Winnebago and State of Illinois, have invented certain new and useful Improvements in Soap-Trays, of which the following is a specification.

This invention relates in general to soap dishes or trays and receptacles of a similar nature, and has more particular reference to the construction of holders or supports for such articles.

These articles are generally manufactured as wire goods, and as such, may be produced very cheaply. One form of soap dish or tray is especially adapted to be detachably supported from and between two faucets, and since these are found to be spaced at different distances apart the supports are made extensible so as to be applicable under all conditions. It is found, however, that in handling these trays in the factories, stores, etc., the extensible supports often become disengaged from the tray and lost, rendering the tray practically valueless.

In the present invention I have aimed to provide an improved tray of the character described constructed so that it will be impossible for the extensible supports or holders to become detached from the tray.

Another object of my invention is to provide an improved article of manufacture of such simple design that it may be produced at a comparatively low cost and will serve practically and satisfactorily the purpose for which it is designed.

Referring to the drawings in which I have illustrated one practical embodiment of my invention—

40. Figure 1 is a plan view of a soap tray embodying my improvements, showing a portion in section;

Figs. 2 and 3 are side and end views, respectively, of the tray; and

45. Fig. 4 is a perspective view of one of the holders or supports.

The tray or receptacle in connection with which my improvements are embodied may be of suitable form and construction, and in the present instance I have shown a conventional form of soap tray of wire construction. It consists of a rim 5 of relatively heavy gage wire shaped to define a rectangular tray, a plurality of cross wire strands 6 spot welded at their ends 7 to the

underside of the rim 5 and shaped intermediate their ends to provide and define a dished shape of sufficient depth to serve as a soap receptacle, and a longitudinal wire strand 8 also spot welded at its ends 9 to the end portions of the rim 5 and extending beneath and across the wires 6 and being suitably secured thereto to hold their lower portions in fixed relative relation. A tray constructed in this manner is very serviceable, and because of its simplicity in design may be made very cheaply.

It is desired to support a tray such as I have illustrated from and between two spaced faucets ordinarily found in kitchen and bath water supply fixtures. Means are provided for supporting the tray or a similar article between two fixed parts or faucets and are constructed so as to be applicable to such parts spaced different distances apart. The means for holding the tray are adapted to detachably fit over the faucets, and are extensibly but permanently mounted on the tray so that they may be projected from the tray sufficiently to fit over faucets spaced at varying distances apart. One of these holding means is mounted on and extended laterally beyond each end of the tray and may be formed, as shown in Fig. 4, of a single strand of wire shaped to provide ends 85 11 in spaced parallel relation and at its intermediate portion to form loop or hook portions 12 joined by the central depressed loop 13. The portions 12 are adapted to fit over the horizontal piping adjacent to each side of the valve of a faucet and the loop portion extends about one side of the faucet so that a holder may be effectually engaged with and connected thereto. The holders at each end are preferably mounted on the tray by means of tubular sections of small gage piping or the like designated by character 14, which are spot welded or otherwise rigidly secured to the tray in parallel relation, as clearly shown in the drawings. 100 These tubular members are adapted to telescopically receive the ends 11 of the holding or supporting members so that the latter are extensibly mounted on the tray and consequently, may be projected so that their outer 105 ends may co-operatively engage faucets spaced different distances apart. Means are provided for preventing withdrawal of the supports or holders from the members 14 and consist preferably of stops between 110

the members 11 and 14 for limiting the extent of the outward movement of the holders. I have found that a very simple and effective way of forming such stops is by employing wire for the supports or holders of somewhat less gage than the inner diameter of the members 14 and flattening or enlarging the ends 15 of the arms 11 of the supports sufficiently so that they enter snugly in the tubular members 14 and then after the supports have been so entered, by narrowing the ends of the members 14 as at 16. Thus the faucets are connected with the tray in such manner as to enable them to be extended from the tray a distance limited by contact of the enlarged ends 15 of the supports with the narrowed ends 16 of the tubular members. The holders or supports are thereby permanently and extensibly mounted on the tray in an effectual manner, and it will be impossible for the supports to become accidentally withdrawn from the tray. It will be noted that while a very substantial and serviceable article is provided for the purposes desired, the construction is so simple that it is possible to manufacture the article at a comparatively low cost, and it should be understood that while I have shown one particular embodiment of my improvements, details of construction thereof might be changed and modified without departing from the spirit and scope of the invention as expressed in the appended claims.

35 I claim:

1. As an article of manufacture, a tray or the like, a pair of tubular members secured in parallel relation thereto and having re-

duced ends, and a pair of holders for the tray each having a pair of parallel arms adapted to telescopingly enter said tubular members so that the holders are extensibly mounted on the tray, said arms within the tubular members having lateral projections adapted by contact with said reduced ends to prevent withdrawal of the arms from said members.

2. As an article of manufacture, a tray or the like, means for supporting the same including a tubular member fixed to the tray and a narrow supporting member one end of which telescopingly enters the tubular member and the other end of which is adapted to cooperatively engage a fixed support, the supporting member within the tubular member being flattened or enlarged at one point and the tubular member being reduced in cross-sectional area in a manner to prevent withdrawal of the supporting member from, but allowing it to be extensible with respect to, the tray.

3. A holder for a tray or similar article comprising a pair of spaced tubular members fixed to the tray in parallel relation, and a pair of holders each formed of a single piece of wire shaped with its ends in parallel relation and adapted to telescopingly enter the tubular members from a common end thereof, the inner or confined end portions of each holder having a lateral projection and the outer end portions of the tubular members being narrowed so that the holders while being extensibly mounted in the tubular members are precluded from being withdrawn therefrom.

ELMER L. DENNIS,
